PER UTNE, OF EDGEWOOD PARK, PENNSYLVANIA, ASSIGNOR TO THE UNION SWITCH & SIGNAL COMPANY, OF SWISSVALE, PENNSYLVANIA, A CORPORATION OF PENNSYLVANIA.

APPARATUS FOR THE CONTROL OF BRAKES FOR RAILWAY-VEHICLES.

1,105,316.

Specification of Letters Patent. Patented July 28, 1914.

Application filed December 18, 1911. Serial No. 666,394.

To all whom it may concern:

Be it known that I, PER UTNE, a subject of the King of Norway, and residing at Edgewood Park, in the county of Allegheny and State of Pennsylvania, United States of America, have invented certain new and useful Improvements in Apparatus for the Control of Brakes for Railway-Vehicles, of which the following is a specification.

10 My invention relates to apparatus for the control of the brakes for railway vehicles, and more particularly to valve devices embodied in such apparatus and adapted when operated to cause application of the brakes. 15 I will describe one form of valve device embodying my invention, and will then point out the novel features thereof in claims.

In the accompanying drawings, Figure 1 20 is a view showing in section on a vertical plane one form of valve device embodying my invention. Fig. 2 is a view showing the valve device shown in Fig. 1 partly sectioned on the plane indicated by the line 25 II—II of Fig. 1.

Similar reference characters refer to similar parts in each of the views.

One feature of my invention is the provision of a valve in the "train pipe" of a 30 railway vehicle, which valve, when once opened, is held opened by the outflowing fluid pressure until the pressure in the train pipe is reduced to substantially atmospheric pressure.

35 Referring to the drawings, 18 is a valve body which communicates, by means of a pipe 12, with a source of fluid pressure, usually the "train pipe" of a railway vehicle. The valve body contains an annular valve 40 seat 19 against which a valve 23 is biased by means of a spring 24. The inner portion of the valve seat 19 communicates with a passage 20 which passes upwardly around both sides of the valve body 18, as shown in Fig. 45 2, and opens into a chamber 25 from which the escape of fluid is permitted as will now be explained. As here shown, this chamber 25 is formed by the top 21 of the valve body 18 and by a cap 22 adapted to fit freely over 50 the sides of the body 18. The sides of the body 18 are preferably conically sloped as indicated in the drawings, the flange of the cap 22 being also similarly sloped, so that the area for the escape of fluid increases the

farther the cap 22 is raised above the top 21. 55 The cap 22 is provided with a staple 26 by means of which the cap may be raised by a crank arm 27, which crank arm is actuated as hereinafter explained. As shown in Fig. 2 the cap 22 is provided with outwardly extending ears 28 into which are fixed downwardly extending studs 29 which slide in guide holes in lugs 30 formed on the valve body 18. The studs 29 are connected at their lower ends by 60 means of a strap 31. The upward movement of the cap 22 and its attached studs and strap is limited by the engagement of sleeves 32 on studs 29 with the lugs 30. The valve 23 is provided with a downwardly extending valve stem 33 adapted to be engaged by the strap 31. This valve stem is of such length that when the strap 31 is at the lowest position of its movement the valve 23 rests against its seat 19. Obviously 70 then when the strap is raised the valve will be raised from its seat, allowing fluid pressure from the pipe 12 to flow into the passage 20 and chamber 25. The cap 22 is biased to its lowest position by means of a 75 coiled spring 34, the pressure of which spring can be adjusted by a nut 35 which screws into a casing 36, in which the valve device is inclosed.

The operation of the valve device is as 85 follows: Normally the parts occupy the positions in which they are shown in the drawings, so that the valve 23 is closed thereby retaining the pressure in the train pipe or other apparatus with which pipe 12 is connected. When crank arm 27 is raised, it raises the cap 22 and therefore the strap 31, thereby raising the valve 23 from its seat 19. Fluid under pressure is then allowed to pass 90 from the interior of valve body 18 through passage 20 into chamber 25, and thence to atmosphere around the edges of cap 22. The area of the cap 22 is sufficient to enable the escaping fluid to provide the pressure required to hold the cap 22 in the raised position, against the action of gravity and of the springs 24 and 34. That is, the valve 23 is held open by the pressure of the air in chamber 25. As the pressure gradually decreases, cap 22 gradually closes, this cap acting as 100 a throttle to constantly maintain sufficient pressure in the chamber 25 to hold the valve open. The valve 23 is therefore held un- 105

seated by the strap 31 until the flow of fluid ceases, that is, until the pressure in the train pipe is reduced to substantially atmospheric pressure, and the cap 22 and valve 23 then 5 resume their normal closed position under the influence of gravity and of springs 34 and 24. It will be seen therefore that when the valve device 11 is once opened, it remains open until the pressure in the train pipe is 10 practically exhausted and the brakes applied. It will be seen further that the valve device is held open solely by the pressure of the outflowing fluid, and that the operation of the valve device is therefore entirely 15 automatic after being opened.

The crank 27, which operates the valve device, may be actuated in any suitable manner. As here shown this crank is fixed to a shaft 37 which is mounted to oscillate in 20 bearings carried in a housing 38, which housing is rigidly mounted in the inclosing casting 36. Rigidly secured to the shaft 37 at its outer end is another crank arm 39, which is arranged to be engaged by a stop arm 25 located in the trackway; the stop arm may, for example, be of the type shown and described in my co-pending application, Serial No. 752,897, filed March 8, 1913, which is a division of the present application.

30 It is often desirable to provide automatic means for recording the number of operations of a brake controlling apparatus. In Fig. 1 I have shown one form of such means which is actuated by the fluid pressure 35 escaping from the valve device. A passage 47 leading out from the passage 20 connects with a chamber 48 in which is located a flexible diaphragm which is responsive to the pressure in the passages 20 and 47.

40 This diaphragm is operatively connected with a stem 49, the outer end of which engages the short arm of a pivoted lever 50. This lever 50 is operatively connected with a counting device 51 in the manner clearly 45 shown in the drawing. By the use of the fluid pressure exhausted from the train pipe through valve 23 to operate the counter, I provide a simple and reliable method, and avoid the necessity of complicated mechanical connections between the counter and 50 some moving part of the apparatus.

Although I have herein shown and described only one form of valve device embodying my invention, I do not wish to be 55 limited to this specific form; it is understood that various modifications may be

made therein within the scope of the appended claims without departing from the spirit and scope of my invention.

Having thus described my invention, what I claim is:—

1. In an apparatus for the control of fluid pressure brakes, the combination with a train pipe of a valve in the train pipe biased to closed position, means for opening the valve; a chamber into which the valve exhausts; said chamber comprising a stationary member, and a movable member operatively connected with the valve and fitting loosely over the stationary member whereby the valve will be held open by the outflow of fluid through the valve.

2. In combination, a fluid pressure receptacle, a valve in said receptacle biased to the closed position, a chamber into which said valve exhausts; said chamber comprising two members one of which has conical sides and the other a conical flange adapted to fit over said conical sides, one of said members being fixed and the other movable, whereby the area of the opening between said members varies in accordance with the position of the movable member; and connections interposed between the movable member and the valve for holding the valve open a variable amount according to the position of said movable member.

3. In combination, a valve body, means for supplying fluid pressure thereto, a valve in said body biased to the closed position, an exhaust passage in the wall of said body leading from said valve to one of the outside faces of said body, a movable cap fitting over said face and forming with the face a chamber into which the valve exhausts, the opening from said chamber to atmosphere varying in area according to the position of said cap, means for biasing said cap to the closed position, connections interposed between the cap and the valve for holding the valve open a variable amount according to the pressure in said chamber, and means for raising said cap from the said outside face of the body and thereby opening the valve.

In witness whereof, I affix my signature in presence of two witnesses.

PER UTNE.
